US00D614601S

(12) **United States Design Patent**
Kataoka et al.

(10) **Patent No.:** US D614,601 S
(45) **Date of Patent:** ** Apr. 27, 2010

(54) **SOIP (SERVICE OVER IP) PHONE**

(75) Inventors: **Tetsu Kataoka**, Tokyo (JP);
Kyung-Hoon Lee, Seoul (KR);
Tai-Hyung Ju, Seoul (KR)

(73) Assignee: **Samsung Electronics Co., Ltd.**,
Kyunggi-do (KR)

(**) Term: **14 Years**

(21) Appl. No.: **29/315,565**

(22) Filed: **Jul. 6, 2009**

(51) **LOC (9) Cl.** **14-03**

(52) **U.S. Cl.** **D14/142**; D14/130
